UNITED STATES PATENT OFFICE.

WILLIAM H. SCOTT, OF TORONTO, CANADA, ASSIGNOR OF ONE-HALF TO
HESTER VEALE HARDY, OF SAME PLACE.

CLOTHES-STICK.

SPECIFICATION forming part of Letters Patent No. 398,089, dated February 19, 1889.

Application filed July 7, 1888. Serial No. 279,274. (No model.)

To all whom it may concern:

Be it known that I, WILLIAM HENRY SCOTT, jeweler, of the city of Toronto, in the county of York, in the Province of Ontario, Canada, 5 have invented a certain new and Improved Clothes-Stick, of which the following is a specification.

The object of the invention is to construct a clothes-stick of that class by which each 10 separate article in the boiler may be grasped and the water therein partially removed therefrom before it is removed from the boiler; and it consists in the peculiar combination and construction of parts, all as more fully hereinafter described and claimed.

Figure 1 is a perspective view of a wash-boiler and of my improved clothes-stick as it 15 will appear in its normal position before seizing an article. Fig. 2 is a similar view showing my clothes-stick in the act of removing an article from the boiler.

A represents two metal stocks pivoted together, and B represents two sticks fitted into sockets formed in the stocks A.

C represents two shorter sticks fitted into sockets formed in the opposite ends of the stocks A.

D is a spiral spring connected to the ends of the sticks C and arranged so that the tension of the spring shall hold the sticks open, as shown in Fig. 1.

I do not wish to confine myself to the exact

form or position of the spring shown, the only function of the spring being to hold the sticks open, as before mentioned.

In order to get a good grip on the article to be removed from the boiler E, I prefer to cross-flute the sticks, as indicated in the drawings, or longitudinal flutes may be made in the said sticks; but I do not claim the fluting 35 as any part of my invention.

On reference to Fig. 1 it will be noticed that only one hand is required to use my improved stick, and that a single article may be readily gripped, and by twisting the stick the 40 article so gripped may be freed of much of the surplus water before the article is removed from the boiler.

What I claim as my invention is—

The clothes-stick described, consisting of 50 the stocks A, pivotally connected together and formed with sockets, the sticks B, fitted into the sockets at one end of said stocks, the shorter sticks C, fitted into the sockets at the other end of said stocks, and the spiral 55 spring connecting the ends of said shorter sticks, substantially as and for the purpose specified.

Toronto, June 19, 1888.

W. H. SCOTT.

In presence of—

CHARLES C. BALDWIN,
J. M. JACKSON.
